COMBINED X-RAY AND FLUOROSCOPIC APPARATUS

Leo Mackta, Brooklyn, N. Y.

Application November 9, 1946, Serial No. 708,886

12 Claims. (Cl. 178—6.8)

1

This invention has for its principal object the production of an X-ray fluoroscopic apparatus for permitting detection and visual inspection, for indefinitely long periods of time, of a normally invisible object or entity, such as a fractured bone or a foreign object in the body, or hidden defects or internal flaws in an object such as in a metallic shaft or the like, without injury to the patient, operator, or others, who ordinarily might suffer injury when subjected to the deleterious effects from overexposure to the intensity of an X-ray beam. The results achieved by means of the invention, accordingly, are equally efficacious when the invention is practiced either in the field of medicine and surgery or industrially.

A further object of the invention is the production of an X-ray fluoroscopic apparatus of the character above described which may be effectively operated with a current of relatively small volume to thereby obviate danger of overheating of the X-ray tube and adjacent parts and to minimize the expense of operation.

A further object of the invention is the production of an X-ray fluoroscopic apparatus so constructed and so operating as to permit continuous visual inspection of the image of the object examined in daylight or under normal room lighting, as in an operating room, without necessitating the adaptation of the operator's eyes to the existing light and to thereby facilitate surgical removal of buried foreign bodies or the setting of fractured bones.

A further object of the invention is an improved method of practicing X-ray fluoroscopy whereby the above and other desired results may be achieved.

A further object of the invention is the production of an X-ray fluoroscopic apparatus of the character described which may be portable and easily adapted for field use because, among other things, of the substantial reduced transformer power required for the X-ray tube and the consequent decrease in the weight of necessary equipment ordinarily required in X-ray fluoroscopy.

Still a further object of the invention is the provision in an apparatus of the above character of a movable gas counter tube the movement of which is synchronized with the vertical reciprocating movement or "frame rate" of the scanning mechanism employed thus enabling the use of a much smaller counter tube than ordinarily would be necessary.

A further object of the invention is the inclusion in an apparatus of the above character

2

of means for expediting the deionization of the counter tube immediately after each ionizing event occurs to thereby enhance the efficiency of the tube and render it capable of operating with sufficient rapidity to enable it to keep pace with the operation of the scanning mechanism in the organization of the elements of the invention.

Further and other objects and advantages of the invention will appear from the accompanying description, the invention consisting in the novel X-ray fluoroscopic apparatus and method of practicing X-ray fluoroscopy hereinafter more particularly described and then specified in the claims.

15 In the accompanying drawings illustrating a practical embodiment of the invention:

Fig. 1 is a perspective view of the apparatus with its accompanying electrical operating and synchronizing circuits.

20 Fig. 2 is an enlarged perspective view of a modification of some of the parts of the apparatus.

Fig. 3 is a perspective view of the X-ray tube.

Fig. 4 is an electrical diagram of a modified 25 circuit for the gas counter tube, such as that of the Geiger-Mueller type, functioning as a uniform pulse generator operating on a voltage exceeding that of the threshold voltage.

Fig. 5 are diagrams showing the characteristic 30 curves of the phase relationship between the counter tube applied voltage, the X-ray beam intensity and the plate voltage of the thyratron tube, when the apparatus operates according to the modification of Fig. 4.

35 Fig. 6 is an electrical diagram of a modification of the circuit of Fig. 4.

In practicing the instant invention, advantage is taken of the extreme sensitivity to X-ray radiations of a gas counter tube such as that of the Geiger-Mueller type, permitting it to detect and record the densities of the elements of an image created by an X-ray beam penetrating a normally opaque object or entity. The passage of this X-ray beam into the sensitive volume intermediate the electrodes of the counter tube will be manifested in the form of a succession of electrical impulses produced by abrupt changes in voltage of the central wire or anode of the counter tube brought about by successive ionizations of the gas contained in the tube. The electrical impulses so produced subsequently are re-created, as will be presently described, in the form of visible light areas corresponding to the elements of the image of the object studied,

which permits continuous visual inspection of the image.

According to the invention, also, the invisible object or entity examined is at no time subjected to the full intensity of the X-ray beam but to a single ray only of said beam at any given instant or fraction of an instant of time and the penetrating rays are projected through the object examined in very rapid succession both vertically and laterally and immediately adjacent to each other over a predetermined area to initially create an invisible image of the examined object. The method employed simulates somewhat the mechanical horizontal and vertical scanning of the reflected light rays of the elements of a visible entity as received by a photoelectric cell or similar detector and as utilized in a television type receiver, the distinction being, however, that in the instant invention the repeating action is provided for the individual penetrating rays or radiations of an X-ray beam generated by an X-ray tube and projected from its target through the invisible examined object. In the television apparatus, the normally opaque object examined is not interposed between the scanning device and the light detector as in the present case, where a gas counter tube is placed behind the examined object.

Referring in detail to the drawings:

The vertical and horizontal members of any suitable type of support are indicated at 10 and 11 respectively. Fastened to the vertical member 10 is an angled strut 12 which rigidly carries a shield 13 comprising an opaque plate composed of a lead-like material impervious to the passage therethrough of the rays of an X-ray beam generated by a conventional X-ray tube 14 shown more clearly in Fig. 3. Said tube is positioned adjacent the plate 13 and is provided with the usual heating cathode 15 and anode or target 16, preferably of tungsten, as well as the focusing cup or cylinder 17 for confining the electrons emitted by the heating cathode within a limited area and for directing them against the inclined face of the anode-target 16 which in turn generates the X-rays and directs the beam thereof tangentially in the direction of an aligning rectangular aperture or opening 17' in the vertical plate 13 through which a portion of the primary rays of the beam pass. The target spot of the anode 16 is the radiant point of the conical beam or pencil of rays generated by the X-ray tube so that any given ray of that beam originates at that point.

The heating cathode 15 and anode 16 of the X-ray tube are connected to suitable insulated conductors 18 which may support the tube and which in turn are supported by a bracket 19 fastened to the strut 12. Said conductors 18 are connected to a source of high voltage well filtered direct current, (not shown) and having, for most purposes, a potential of from 75,000 to 100,000 volts. Because of the sensitivity of the gas counter tube employed in the system of the invention, however, the volume of current could be as low as 5 milliamperes instead of 25 to 100 milliamperes usually required in X-ray fluoroscopy and radiography. It is important nevertheless, that the current be well filtered as any voltage ripple will result in a corresponding ripple in the X-ray radiations which are impressed on the detecting instrumentalities of the system and will finally manifest themselves as distortions in the image of the object or entity examined. Because of the small X-ray tube current required, adequate rec-

tification and filtering of the high voltage current should not be difficult.

A rotatable drum composed of a lead-like material opaque to X-rays is indicated as 20. Said drum is provided with a plurality of pin-holes 21 in the annular wall thereof which are equally spaced from each other and from the upper peripheral edge of the drum. Said pin-holes 21 are positioned so as to be in alignment with the target spot of the anode 16 of the X-ray tube and with the rectangular aperture 17' in the shielding plate 13 as the annular wall of the drum revolves around the drum axis whereby a single ray of the X-ray beam, represented in dotted lines for instance at 22, passes or is projected through one of the pin-holes at any given instant and through the object or entity being examined which for clarity of description only is here represented as the lower portion of a leg 23 of a person. No precise number of pin-holes 21 is necessary as the number may vary to suit varying conditions.

The drum 20 just described is rotated by a conventional motor indicated diagrammatically at 24 the motor shaft of which is connected to a conventional reduction gear and right-angled drive (not shown) within a gear box 25 which gearing is operatively connected to the drum shaft 26 which is fixed to the drum. The pin-holes 21 in the annular wall of the drum accordingly are revolved around the axis of the drum shaft as a center and one of them is at all times in alignment with the target spot of the X-ray tube. The base of the drum is cut out at spaced intervals to provide fan blades 27 constituting air-cooling elements for cooling the X-ray tube 14 by circulation of air around it, as the drum rotates with its shaft 26. The shaft of the motor is also connected through a conventional reduction gear and right-angled drive (not shown) contained in a second gear box indicated at 28 which mechanism is also connected to a horizontally extending rotatable shaft 29 carrying a cam 30 which is fixed thereon. The configuration of the peripheral edge of said cam is best illustrated in Fig. 2 with its lowermost point indicated at 30'. Said edge constantly engages a roller 31 journalled in the arms of a bracket 32 which is fastened to vertical member 10 of the support previously referred to.

50 A U-shaped bracket is indicated at 33 and is fastened to the gear box 25 and loosely receives the rotatable drum shaft 26 therethrough. Said bracket 33 is provided with upwardly extending parallel arms 34. An additional bracket for pivotally supporting the entire drum and motor assembly is indicated at 35 and is bolted or otherwise secured to the vertical member 10. Said supporting bracket 35 is provided with outwardly extending supporting arms 36 which are pivotally connected, as by pins or pivots 37, to the upper ends of arms 34, the pivoted connections being such that the longitudinal axis of the pivots 37 are in horizontal alignment with the target spot of the anode 16 of the X-ray tube.

65 A disc commutator is indicated at 38. It is carried by and rotates with the drum shaft 26 and it is the reverse of a conventional commutator in that electrical contact is made with the smaller of the contact segments 39 on its periphery rather than with the intermediate broader segments 40 which are composed of an insulating material. The number of contact segments 39 equals the number of pin-holes 21 in the wall of the drum 20 and said segments are connected together by a conducting ring 41 which in turn

is connected by conducting wire 42 to a metallic slip ring or collector 43 carried by but insulated from shaft 26. A contact strip or brush is indicated at 44. The free end of said contact strip engages and makes slidable contact with the slip ring 43 while the other end is connected to one of the arms 34 of bracket 33. A second contact strip or brush is indicated at 44' and is provided adjacent its free end with an angled contact member 45 adapted to successively engage the contact segments 39 as the commutator rotates. The opposite end of said brush 44' is connected to but insulated from the other of the arms 34 of bracket 33.

A tension spring is indicated at 46 and its ends are attached to an arm 34 of bracket 33 and a supporting arm 36 of bracket 35 and it acts to swing the entire suspended drum and motor assembly on pivots 37 and in the direction of vertical member 18 by a snap action when the roller 31 engages the lowermost point 30' of the edge of the cam 30. A solenoid 47 has also been provided for a purpose to be described. It is supplied with the usual external winding 48 and it is fastened to the horizontal support by a U-bracket 49. The movable core of said solenoid is tapered and is indicated at 50 and it is held and supported by a strip 51 fastened to the gear box 25 so that a free reciprocating movement is imparted to said core within the solenoid to change the inductance of coil 48 when the drum and motor assembly oscillates or rocks on its pivots 37.

The degree of rocking or oscillation of the drum and motor assembly on pivots 37 is relatively small, the amplitude of oscillation being determined by the height of the aperture 17' in plate 13, that is, the distance between the horizontal walls of said aperture which distance also defines the limits of the relative vertical position of any given ray of the X-ray beam passing through said aperture. A forward pivotal movement of the drum and motor assembly on pivots 37 is brought about positively by engagement of the high side of the edge of the cam 30 with roller 31 while a reverse movement in the opposite direction to swing the drum and motor assembly towards the vertical member 18 is effected partially by the action of the spring 46 when roller 31 engages the lowermost point 30' of the cam edge. The motor and drum assembly is shown in approximately neutral position in Fig. 1 and each cycle of a complete oscillation on pivots 37 may be referred to hereinafter as the "frame rate" of the vertical scanning operation.

The relative ratio of the gears in gear box 25 is such that approximately 150 pin-holes 21 are brought into alignment with aperture 17', each for passage of a single ray of the X-ray beam therethrough, during each cycle of oscillation of the drum and motor assembly on pivots 37. This number is arbitrary and indicates approximately the speed of rotation of the drum 20 and it is not an indication that the number of pin-holes may not be varied. The dimensions of the aperture 17' are such that immediately when one pin-hole passes out of alignment with the aperture or beyond its lateral limits as defined by its width, the next succeeding pin-hole enters the opposite lateral limit of the aperture. This relative movement of the pin-holes with respect to the aperture 17' through which the X-ray beam is projected may be referred to as the horizontal scanning operation. The relative ratio of the reduction gears in gear box 28 is such that the drum and motor assembly, because of the action of the cam

30 and spring 46, may complete a full cycle of oscillation on pivots 37 about once every second which is given as an example only and may be varied. In practice, the horizontal scanning operation is relatively much more rapid than the vertical scanning or frame rate.

The reference numeral 52 indicates a sensitive detector in the form of a gas counter tube which preferably is of the Geiger-Mueller type. The gas contained in the tube is one which produces a large yield of ions when subjected to the intensity of the rays of an X-ray beam of the hardness commonly used for radiography and fluoroscopy. A mixture of argon and ether is suitable for the purpose although other gases or mixtures thereof may be used effectively. The cathode 53 of the counter tube may be of brass and is in the form of a cylinder or semi-cylinder having a projected area facing the X-ray beam of a size so as to include within it the area of radiation as measured and defined by the pin-holes 21 and the size of the aperture opening 17'. The anode or central wire 54 of the counter tube may be of tungsten. It extends longitudinally of the tube and is concentric with the longitudinal axis of the cathode 53. The envelope of the tube may be of the type of glass or aluminum metal which will readily permit the passage of X-ray radiations therethrough with maximum efficiency.

In some cases where a counter tube of relatively small size is employed it will be found desirable to reciprocate it vertically and synchronously with the rocking or frame movement of the drum 20 to insure that the penetrating rays of the X-ray beam will not escape entering the sensitive region of the counter tube as the counter tube then will follow the vertical scanning operation. A mechanism for effecting a movement of this character is illustrated in Fig. 2 in which 55 indicates a tube-carrying frame, the vertical or side members of which have the upper and lower shafts 56 and 57 respectively journaled therein. On their outer ends, said shafts carry upper and lower rollers 58 and 59 respectively, each pair of rollers being connected together by an endless belt 60 which is held taut. Each belt carries a block 61 provided with a strap or clip 62 for supporting the counter tube 52. The lower shaft 57 carries a bevel gear 63 meshing with a bevel gear 64 the vertical shaft 65 of which is journaled in the lower horizontal wall of the frame 55.

The strip 51 previously described may be provided with a right-angled extension 66 carrying a curved rack 67 whose radius of curvature is concentric with the longitudinal axes of pivots 37, said rack meshing with a pinion 68 whose shaft 69 is journaled in a bracket 70 which may be fastened to the horizontal member 11. A flexible drive shaft 71 is supported by a bearing member 72 and connects shafts 65 and 69 so that, as is obvious, rocking or oscillation of the drum 20 on its pivots 37 effects vertical synchronous reciprocation of the counter tube 52. Flexible electrical conductors 73 and 74 are connected to the wire and cylinder of the counter tube and to insulated binding posts 75 and thence to the circuit of Fig. 1 about to be described.

Again referring to Fig. 1, 76 indicates a source of high voltage direct current which is connected to the electrodes of the counter tube 52 for operation of the tube. The current developed through the counter tube by successive ionizations of the gas therein to generate electrical impulses conforming to the elements of the image of the invisible object examined, as a bone in the leg 23,

by the rays of the X-ray beam, produces a voltage drop across the high resistance 71. The voltage is impressed on the control grid of a suitable pentode mixer tube 78 through a bias battery 79 which brings the voltage on the control grid to a desirable value for the operating characteristics of the mixer tube. A conventional carrier frequency oscillator having a frequency approximating 100 kilocycles is indicated at 80 and is electrically coupled to the second grid of the mixer tube 78 through a condenser 81. A high resistance is indicated at 82 and is included in the return circuit for the oscillator and grid current, its purpose being to apply a desirable D. C. voltage to the second grid of the mixer tube. The plate current of said mixer tube 78 passes through a transformer 83 and is caused to flow by a battery 84. The function of the transformer 83 is to "match" the plate impedance of the mixer tube 78 to a coaxial transmission line 85, that is, to reduce the plate impedance to a value where it will feed said coaxial transmission line. All of the components numbered from 76 to 84 inclusive constitute the preamplifier of the system which is positioned as close to the Geiger-Mueller counter tube as is conveniently possible. Said preamplifier acts to bring the level of the signal output of the counter tube 52 to a value where it may be transmitted over the conveniently long coaxial transmission line 85 to be amplified and viewed on a fluorescent screen as will be presently described.

The output of the preamplifier as obtained from the coaxial transmission line 85 consists of a modulated signal of a frequency generated by the oscillator 80, the modulations being those impressed on the mixer tube 78 by any variations in the ionizing current in the counter tube 52. Variations in the ionizing current in the counter tube occur from variations in the intensity of the rays of the X-ray beam as they scan the different radiodensities of the entity 23 under examination.

The coaxial transmission line 85 terminates in the input of a conventional broad band amplifier 86, preferably of the video type, having a frequency range many times that of an ordinary amplification system. Said broad band amplifier 86 amplifies the signals received by it to a desirable level and feeds those signals to a conventional second detector circuit which is direct-coupled to another stage of amplification for controlling the intensity grid of a cathode ray television type tube. This detector and amplifier is indicated at 87 and the cathode ray tube at 88. The function of the detector and amplifier 87 is to eliminate the carrier frequency and to re-create the shape of the impulses generated by the counter tube 52. Said cathode ray tube 88 is provided with the usual fluorescent screen 89 on which the image of the object examined is made visible. The phosphor on said screen is of the persistent type, the duration of its persistence being determined by the frame or vertical scanning rate previously referred to.

The sharply focused beam of electrons modulated in the cathode ray tube 88 by the impulses of the counter tube in the manner described is deflected vertically and horizontally by its conventional pairs of vertical and horizontal deflecting plates 90 and 91 respectively by changes of voltage impressed on said plates. The impulses for horizontal synchronization are derived from commutator 38 the contact segments 39 of which are successively engaged by the angled contact member 45 of contact brush 44' and the contact brush 44 which engages the metallic slip ring 43. The

impulses for frame or vertical synchronization are derived from the changes of impedance of coil 48 of solenoid 47 brought about by the reciprocation of the tapered core 50 in said solenoid when the drum and motor assembly oscillates on pivots 37.

A resistance 92 and battery 93 are connected in series with the brushes 44 and 44'. At each instant one of the segments 39 is engaged by the contact brush 44' a voltage is developed across said resistance 92 to trigger or synchronize a conventional relaxation oscillator indicated at 94 which generates a voltage having a saw-tooth wave form which is impressed on the horizontal deflecting plates 91 of the cathode ray tube 88.

For the frame or vertical synchronization, a source of alternating current 95 is provided whose frequency is in the neighborhood of 60 cycles or higher. This source of current is connected to the winding on the solenoid 47 and to a transformer 96. The current in the primary of the transformer is then varied as a result of the change in the impedance of the solenoid by virtue of the movement of its core therein. Said core 50 is so tapered that the final voltage which will be shown to be applied across the vertical deflection plates 90 of the cathode ray oscilloscope tube 88 varies in direct proportion to the angle of oscillation of the drum 29 on its pivots 37.

The alternating current voltage developed across the secondary of transformer 96 is rectified by a conventional bridge type rectifier 97 and the rectified voltage is filtered by a condenser 98 to eliminate the usual ripple. The combination of the condenser 98 and a resistance 99 has a period such that the voltage across the deflection plates 90 will closely follow the variations of voltage brought about by the movement of the iron core 50, yet will effectively filter the higher frequency ripple set up by the source of alternating current. The voltage thus produced across resistance 99 is applied to the vertical deflecting plates 90 of the cathode ray oscilloscope tube 88 through a battery 100 which corrects the voltage to a proper value to center the neutral position of the electron beam on the screen 89 of the oscilloscope.

The mode of operation of the apparatus will be apparent to one skilled in the arts of electronics and television. The rays of the electron beam in the cathode ray oscilloscope 88 scan the fluorescent screen 89 of the tube synchronously with the scanning of the penetrating rays of the X-ray beam through the invisible object being examined. The spacing of the pin-holes 21 in the drum 28 is such that as any given pin-hole passes beyond the limits of the X-ray beam as defined or restricted by the width of the aperture 17', the next succeeding pin-hole just enters the opposite limit of the beam. For the vertical scanning operation, the diameter of the pin-holes is such that the individual rays of the X-ray beam passing through successive pin-holes just touch or impinge on each other as the scanning operation proceeds. It will be noted also that in both the horizontal and vertical scanning, the longitudinal axis of the drum shaft always intersects the longitudinal axis of any given ray of the X-ray beam passing through the aperture 17'. Said rays are permitted to pass through the pin-holes only and they are completely obstructed elsewhere.

The variations of intensity of the X-ray beam brought about by the penetration of the rays through the invisible object examined, such as bone, muscle, bullets or other foreign objects, when the apparatus is used in surgery for in-

stance, cause similar variations in the ionizing current in the Geiger-Mueller counter tube 52. These current variations are then amplified in such manner as to control the intensity of the electron beam in the oscilloscope 88 resulting therefrom and which illuminates the fluorescent screen 89 of said oscilloscope tube and permits visual inspection of the image of the entity examined on said screen. Since the phosphor of the screen 89 is persistent for the duration of a frame, the image will remain constant on the screen for each frame and will be recreated for the next succeeding frame. There will be a blending of the old and new images thus created to exhibit a smooth change even if the examined object is moved slowly. The fluorescent screen may be illuminated brightly by the employment of a high accelerating voltage for the beam in the oscilloscope tube and the diameter of the screen may be varied to suit one's convenience.

Should the apparatus be used for exhibiting the image of the object examined to a large audience, a plurality of cathode ray oscilloscope tubes may be connected to the output of the video amplifier and to the synchronizing circuits to reproduce the image of the object examined at a number of separated places. Furthermore, a photographic film or plate may be placed against the screen of the cathode ray tube to photograph the image, or a camera may be focused on the screen for the same purpose. Should it be necessary to inspect a relatively small portion of the invisible object examined with more detail, that can be accomplished by positioning the object in closer proximity to the drum mechanism.

When the apparatus is employed for surgical manipulation, such for instance, as the reduction of fractures or foreign body removals, the patient, surgeon and others are free from danger of over-exposure to the X-rays as it has been estimated that the total radiation passing through exposed tissue will approximate 2×10^{-6} that which would be required for ordinary X-ray fluoroscopy. The number and size of the pin-holes 21 employed, the size and speed of rotation of the drum 20 and the size of the reduction gears and cam mechanism obviously may vary to meet varying conditions but it is desirable that the characteristics of the parts be such as to give the substantial equivalent of 150 to 200 line scanning at one frame per second.

The operation of the apparatus has been described when the Geiger-Mueller counter tube 52 operates as a proportional counter having an operating voltage across the counter which generates a pulse size proportional to the number of ions formed in the initial ionizing event. It may be desirable in some cases, however, to operate the counter tube in the Geiger or the most sensitive region of operating voltage and in which the size of the pulse is independent of the number of ions produced in the initial ionizing event. When operating in the Geiger region, the amplification of the counter tube is increased considerably.

According to the method to be described and when the counter tube operates in its Geiger or most sensitive region with its voltage exceeding that of threshold value, graded variations of brilliancy of the image of the invisible object examined may be obtained on the fluorescent screen of the cathode ray oscilloscope irrespective of the "all or none" character of the discharge in the counter tube. Additionally, means are employed whereby the pulse frequency response of the counter tube is considerably increased by ap-

plying a reversed voltage to the counter tube during part of the cycle to sweep up the positive ions collected about the central wire 54 of the counter tube formed by the avalanche process upon the occurrence of an ionizing event and return them a relatively short distance to the wire. The firing rate of the counter tube, accordingly, is considerably accelerated. By employing this reversed voltage the number of scanned lines per second of the invisible object examined may be increased to give more detail to the image of the object and the frame rate may also be increased to follow rapid motions of the examined object. Most of the other previously described components of the apparatus such as the drum and motor assembly, synchronizing circuits and oscilloscope tube are identical in this alternative method, the operating circuits of the X-ray tube and counter tube only being modified.

With reference to Figs. 4 and 5, the X-ray tube 14 is supplied with high voltage from a conventional transformer 101, rectifier tube 102 and condenser 103. In addition, a saw-tooth wave generator 104, preferably operating on a frequency of 20 kilocycles or higher, is employed which is electrically connected to the focusing cup or cylinder 17 of the X-ray tube, the configuration of the wave generated by said generator 104 being indicated at 105 to the right of that element. The cross-sectional density of the stream of electrons or the electronic beam emitted from the heating cathode of the X-ray tube changes rapidly and intermittently to follow the saw-tooth wave 105 and the width of said beam striking the anode target 16 changes periodically from a wide beam to a sharp one because of the variation in voltage applied to the focusing cup 17 of the X-ray tube although the total current remains substantially constant. As the width of the electronic beam varies, the area of the target spot of the anode target 16 varies proportionately to thereby vary the intensity of the X-ray beam produced by each point of the target and thus increase or decrease the intensity of that beam and its individual rays which are projected through the pin-holes 21, through the object examined and into the counter tube 52. This comes about because a relatively small portion of the focal point of the target is the source of any single ray of the X-ray beam which passes unobstructedly through and is confined by any given pin-hole at any given instant. The effect, accordingly, is the production of an X-ray beam the intensity of which varies periodically and rapidly from a relatively small value to a relatively large value many times during the scanning of a single line of the invisible object examined. In practice it will be found desirable to adjust the total X-ray tube current so that the amount of radiation projected into the counter tube 52, after penetration, for instance, of an examined object of medium radio-density, such as a small bone, is sufficient merely to cause the counter tube to discharge when the X-ray beam has a value about mid-way between its minimum and maximum intensity.

For supplying current to the counter tube 52 in the modified apparatus it will be found desirable to employ a common square wave generator 106 connected so as to produce a stronger negative pulse as compared with the polarity and voltage of the battery 107 so that its voltage output resembles the shape of graph 108 shown at the right of that element. The total action of battery 107 and the square wave generator 106 in-

cluding a resistance 109 interposed between the generator and battery produces an effective counter tube voltage whose variations resemble those shown in Fig. 5. The action of the reversed polarity of the voltage impressed on the counter tube is to quickly sweep up the positive ions of the gas in the counter tube after each firing and as previously explained to enable the tube to re-fire expeditiously. The square wave generator 106 is synchronized with the saw-tooth wave generator 104 through conductor 110. Fig. 5 shows the phase relationship of the counter tube applied voltage indicated at 111 as compared with the approximate variations in the intensity 112 of the rays of the X-ray beam.

A triode is indicated at 113 and is of the usual type. Its function is to act as an amplifier for the pulses generated by the counter tube 52. These pulses are transmitted to the grid of the triode through a resistance 114. A thyratron gas tube is indicated at 115. Said thyratron is coupled to the triode 113 through a conventional coupling circuit including batteries 116 and 117, resistances 118 and 119 and condenser 120, requiring no detailed explanation. The thyratron is also biased to prevent it from firing excepting only when an impulse is conducted to it by triode 113. In some cases, and as shown in Fig. 6, it may be found desirable to connect the counter tube 52 as one arm of a conventional capacity-resistance bridge, including the usual resistances 120' and condenser 120'', to balance out its purely capacitative component, particularly if the dimensions of the elements of the counter tube are such that its electrical capacity is sufficient to produce an appreciable pulse on the grid of triode 113 solely as the result of the voltage variations conforming to those illustrated in Fig. 5. In those cases the input to the bridge would be the voltage generated by the battery 107 and the square wave generator 106 in series and the output would be connected from the grid to the cathode of triode 113.

The plate voltage which is applied to the thyratron 115 is varied in a saw-tooth manner from a combination of the saw-tooth wave generator 104, battery 121 and resistance 122. The battery 121 is connected in opposite polarity to the direction of current from the saw-tooth wave generator 104 whereby the effective plate voltage on the thyratron 115 varies approximately as shown in Fig. 5. Its phase relationship with the counter tube voltage and X-ray beam intensity is illustrated at 123 in that figure. The output of thyratron 115 is coupled through a condenser 124 to the video amplifier 125 which is connected by conductors 126 to the cathode ray oscilloscope 88 previously described. Said video amplifier operates to control the brilliance of the spots or elements conforming to the image of the invisible object examined and which are visibly reproduced on the fluorescent screen 89 of the oscilloscope.

The operation of the apparatus when operating according to the modification of the invention is as follows:

Assuming that a material or object of low radio-density is to be examined and is interposed between the X-ray tube and the counter tube, the intensity of radiation which passes through the object and into the counter tube may be relatively small in order to cause the counter tube to discharge, the intensity increasing and decreasing periodically in the manner previously described and following the graph 112 of Fig. 5. The triode 113 amplifies the pulse

created by the discharge and applies it to the grid of thyratron 115. The amplitude of this pulse is so large that it will fire the thyratron irrespective of the amount of its plate voltage in excess of that required for firing. The amount of current passing through the thyratron at the instant it fires is dependent on the value of its saw-tooth wave plate voltage at that instant.

For the case in example, the amplitude 127 in Fig. 5 is illustrative of the intensity of the X-ray beam at the instant the counter tube discharges. The amplitude 128 indicates the approximate value of the plate voltage on the thyratron 115 for that instant and in consequence 15 is an indication of the size of the corresponding pulse which is produced by the abrupt discharge of said thyratron 115. The video amplifier 125 being coupled to the thyratron thereupon causes an electron beam of proportional intensity to be 20 produced in the cathode ray oscilloscope 88 with a spot of proportional brilliance reproduced on the fluorescent screen 89.

Should the object or material examined be of high radiodensity, the amplitude 129 in Fig. 5 indicates approximately the increase in the intensity of radiation required at the instant the counter tube discharges as the object examined is more resistant to penetration of the rays of the X-ray beam and will absorb and scatter some 30 of the rays. The value of the plate voltage of the thyratron 115 at that instant is indicated by the amplitude 130 and it follows, in consequence, that a spot of much less brilliance will be produced on the fluorescent screen 89 than in the 35 previous example. Accordingly, in this method, a series of spots of graded brilliance conforming to the elements of the image of the object examined are produced on said fluorescent screen 89. If desirable, the capacity of the condenser 124 40 may be increased to a value where the pulse which it transmits from the thyratron 115 to the video amplifier 125 is broadened so that a more or less continuous line is produced on the fluorescent screen 89 rather than a series of spots.

45 The invention claimed is:

1. In an apparatus of the character described, a source of X-ray radiations, a gas counter tube of the Geiger-Mueller type for detecting the elements of an image created by directing said X-ray radiations through an invisible object, a scanning device having a circular series of pin-holes and mounted to both rotate and oscillate and having intersecting axes of rotation and oscillation for selectively directing individual radiations successively through said pin-holes and the invisible object, and said scanning device in all positions of rotation and oscillation being located intermediate said source and counter tube, means for rotating said scanning device, means 50 for oscillating the same, means for amplifying the output of said counter tube, and means for visualizing said amplified output.

2. In an apparatus of the character described, a source of a beam of X-rays, a gas counter tube, 55 scanning mechanism having a series of pin-holes axially converging to a common point coincident with the said source, and said mechanism being mounted to both rotate and oscillate about said common point thereby providing a predetermined 60 two-dimensional sweep of an X-ray beam of constant cross-sectional area throughout the sweep thereof and across an invisible object interposed between said scanning mechanism and gas counter tube to produce electrical pulses by said counter tube conforming to and varied in intensity 70 75

sity in transit throughout the sweep only by the density of the object, means for rotating said scanning mechanism and means for oscillating the same.

3. In an apparatus of the character described, a source of a beam of X-rays, a gas counter tube, scanning mechanism for scanning an invisible object interposed between said scanning mechanism and said counter tube, said mechanism being mounted to both rotate and oscillate thereby providing a two-dimensional beam sweep and said gas counter tube being mounted to have transitional movement in one dimensional direction of the scanning sweep, means for rotating said scanning mechanism, means for oscillating the same, and means connecting the scanning mechanism and gas counter tube so as to impart transitional movement to said tube synchronously with movement of the scanning mechanism in the said one dimensional direction.

4. In an apparatus of the character described, a source of an X-ray beam, a gas counter tube, scanning mechanism positioned intermediate said source and said gas counter tube, said mechanism including a member having a circular series of holes therein around said source for successively receiving individual rays of said beam therethrough and said member also being so mounted as to both rotate around and to oscillate with respect to said source, a shield interposed between said source and said member and provided with an opening therein to limit the cross-sectional area of said beam in its path from said source to said member, means for rotating said member to pass the holes thereof across the beam path through the said opening, and means for oscillating said member to move said holes across said beam path and in a direction transverse to the direction of rotation of said holes whereby any given hole passing said shield opening has components of movement simultaneously in both dimensional directions of said opening.

5. In an apparatus of the character described, a source of an X-ray beam, a gas counter tube, scanning mechanism positioned intermediate said source and said gas counter tube for directing individual rays of said beam through an invisible object and into said counter tube, said scanning mechanism including a rotatable drum substantially concentric with said source of X-ray beam and having pin-holes therein for successively receiving individual rays of the aforesaid beam therethrough, said pin-holes being equally spaced from each other and from an edge of the drum and positioned in alignment with and in a circular series around said source of the X-ray beam, means for rotating said drum, a lead-like shield interposed between said drum and source and provided with an aperture therein in the path of a predetermined arcuate beam sweep from said source to said pin-holes, and means for imparting a rocking movement to said drum synchronously with its speed of rotation.

6. In an apparatus of the character described, a source of X-ray radiations, a gas counter tube of the Geiger-Mueller type for detecting the elements of an image screated by directing said X-ray radiations through an invisible object, a scanning device mounted to both rotate and oscillate and having a circular series of pin-holes therein, said scanning device being positioned intermediate said source and counter tube in all of its positions of rotation and oscillation, means for rotating said scanning device, means for oscil-

lating the same, a cathode ray tube having a fluorescent screen and a cathode ray gun and focusing control electrically connected with said counter tube for providing a cathode ray beam varying in intensity to accord with the intensity of the X-ray radiations received by said counter tube, deflecting plates in said cathode ray tube having electrical connections with said scanning device, and means associated with said scanning device for electrically varying the plate potentials of said cathode ray tube through said electrical connections in predetermined accord with the rotation and oscillation of said scanning device.

7. In an apparatus of the character described, a source of an X-ray beam, means for periodically and intermittently varying the intensity of said X-ray beam, a gas counter tube of the Geiger-Mueller type, an annular member concentric with and rotatable around said source of X-ray beam and mounted to oscillate on a pivot whose longitudinal axis is substantially parallel to said counter tube for successively directing individual rays of said beam both horizontally and vertically through an invisible object to create an invisible image thereof and to produce successive ionizations of the gas in the counter tube conforming to the elements of the invisible image, means for rotating said annular member and means for oscillating the same.

8. In an apparatus of the character described, an X-ray tube for generating a beam of X-rays and comprising a cathode, an anode target and a focusing cup for directing the electrons emitted by said cathode to said anode target, means for supplying electric current to said cathode and anode, a gas counter tube, scanning means between said X-ray tube and counter tube for successively directing the rays of said X-ray beam through an invisible object and into the counter tube to produce successive pulses in said counter tube conforming in intensity to the elements of an image of the invisible object, electronic means electrically connected with said counter tube for recreating its output into a visible image of the object, and means for supplying a current of varying voltage to the focusing cup of said X-ray tube to thereby vary the intensity of the X-ray beam.

9. In an apparatus of the character described, a source of an X-ray beam, scanning mechanism having a member adapted to both rotate and oscillate for successively directing individual rays of said X-ray beam through an invisible object both horizontally and vertically to create an invisible image thereof, means for rotating said member, means for oscillating the same, a gas counter tube in the path of said rays through the object for detecting the elements of the invisible image so created and for generating electrical pulses conforming to said elements, a source of high voltage direct current connected to the electrodes of the counter tube, a preamplifier including a carrier frequency oscillator and a pentode mixer tube coupled to the source of high voltage and one of the electrodes of the counter tube, a broad band amplifier having a high frequency range connected to and for receiving the output of said preamplifier, a carrier frequency eliminator coupled to said broad band amplifier for eliminating the carrier frequency transmitted thereto by the amplifier, a cathode ray tube having an electron gun coupled to the carrier frequency eliminator for recreating the output of said eliminator into an electronic beam conform-

ing to the pulses generated by said counter tube, a fluorescent screen for said cathode ray tube opposite said gun, and deflecting plates in said cathode ray tube with one pair thereof electrically connected to said means for rotating said member and another pair connected to the means for oscillating said member for directing the rays of said electronic beam to said fluorescent screen synchronously with the vertical and horizontal movements of said scanning mechanism.

10. In an apparatus of the character described, an X-ray tube for generating a beam of X-rays and provided with the usual cathode and anode target, means electrically connected to said X-ray tube for periodically varying the cross-sectional density of the stream of electrons emitted by the cathode to vary correspondingly the intensity of the X-ray beam; means in the path of the X-ray beam for projecting individual rays of the X-ray beam progressively through an invisible object to create an invisible image thereof, a gas counter tube in the path of said individual rays for detecting the elements of the invisible image and for producing a succession of electrical pulses conforming in intensity to the elements of said invisible image, a generator connected to and for applying a voltage of intermittent reverse polarity to said gas counter tube for increasing its pulse frequency response synchronously with the variations in the intensity of the X-ray beam, amplifying means connected to the output of said gas counter tube for amplifying the same, and means connected to said amplifying means for recreating said amplified output into a visible image conforming to the aforesaid invisible image.

11. In an apparatus of the character described, a source of an X-ray beam, means connected to said source for periodically varying the intensity of said beam, means in the path of said X-ray beam for projecting successive individual rays of said beam through an invisible object to create an invisible image thereof, a gas counter tube in the path of said individual rays for detecting the elements of the invisible image and for producing a succession of pulses conforming in intensity to the elements of said invisible image; a generator connected to and for applying a voltage of intermittent reverse polarity to said gas counter tube for increasing its pulse frequency response synchronously with the variations in the intensity of the X-ray beam, a capacity resistance bridge connected to said generator and counter tube, means connected with and for amplifying the output of said counter tube, a thyratron coupled to said amplifier, and means connected with and controlled by said counter tube for recreating the output of said thyratron into a visible image conforming to the aforesaid invisible image.

12. In an apparatus of the character described,

a source of an X-ray beam, means connected with said source for periodically varying the intensity of said beam, means in the path of said beam for directing successive individual rays of said beam through an invisible object to create an invisible image thereof, a gas counter tube in the path of the said individual rays for detecting the elements of the invisible image and for producing a succession of electrical pulses conforming in intensity to the elements of said invisible image, a generator connected with and for applying a voltage of intermittent reverse polarity to said gas counter tube for increasing its pulse frequency response synchronously with the variations in the intensity of the X-ray beam, an amplifier connected with and for amplifying the output of said counter tube, a thyratron coupled to said amplifier, means connected with and for applying a varying plate voltage to said thyratron synchronously with the variation in the X-ray beam intensity, and means connected through said thyratron to said counter tube for recreating the output of said thyratron into a visible image conforming to the aforesaid invisible image.
